(57) **CLAIM**

The ornamental design for a chair, as shown and described.

DESCRIPTION

FIG. 1 is a perspective view of a chair according to my new design shown in a first position.

FIG. 2 is a front view of the chair of FIG. 1 shown in the first position.

FIG. 3 is a rear view of the chair of FIG. 1 shown in the first position.

FIG. 4 is a left side view of the chair of FIG. 1 shown in the first position.

FIG. 5 is a right side view of the chair of FIG. 1 shown in the first position.

FIG. 6 is a top view of the chair of FIG. 1 shown in the first position.

FIG. 7 is a bottom view of the chair of FIG. 1 shown in the first position.

FIG. 8 is a perspective view of the chair of FIG. 1 shown in a second position.

FIG. 9 is a front view of the chair of FIG. 1 shown in the second position.

FIG. 10 is a rear view of the chair of FIG. 1 shown in the second position.

FIG. 11 is a left side view of the chair of FIG. 1 shown in the second position.

FIG. 12 is a right side view of the chair of FIG. 1 shown in the second position.

FIG. 13 is a top view of the chair of FIG. 1 shown in the second position; and,

FIG. 14 is a bottom view of the chair of FIG. 1 shown in the second position.

Portions of the chair shown in broken lines are for illustrative purposes only and form no part of the claimed design.

1 Claim, 14 Drawing Sheets
